Filed Nov. 13, 1958, Ser. No. 53,362

Term of patent 14 years

(Cl. D15—3)

FIG. 1

The dominant feature of this design resides in the side panel of the chair within the side arm supporting brace, having an upper smooth area covering the major portion of the side of the seat and having a lower area with horizontal parallel decorative lines as shown.

I claim:

The ornamental design for a barber chair or similar article, as shown and described.
